UNITED STATES PATENT OFFICE.

HENRY P. DILLIG, OF MILLVALE, AND JOSEPH B. HILL, OF BELLEVUE, PENNSYLVANIA.

REPEATER OR MAGAZINE FUSE.

Application filed May 24, 1921. Serial No. 472,186.

To all whom it may concern:

Be it known that we, HENRY P. DILLIG, and JOSEPH B. HILL, both citizens of the United States, residing, respectively, at 5 Millvale and Bellevue, both in Allegheny County, in the State of Pennsylvania, have invented a new and useful Improvement in Repeater or Magazine Fuses, of which the following is a full, clear, and exact description, reference being had to the accompanying drawings, in which:

Figure 1 is a side elevation of a fuse embodying our invention;

Figure 2 is a section on the line II—II of 15 Figure 1; and

Figures 3 and 4 are sections, taken, respectively, on the lines III—III and IV—IV of Figure 2.

Our invention has relation to improvements in fuses, and more particularly fuses 20 of the magazine or repeater type, in which there are a plurality of fuse members adapted to be successively brought into use as a fuse member previously in use becomes destroyed.

The object of our invention is to provide a 25 fuse of this character which will be more simple in its construction and more convenient in its action than other devices of this 30 character with which we are familiar.

The nature of our invention will be best understood by reference to the accompanying drawings, in which we have shown a preferred embodiment thereof, which will 35 now be described, it being premised, however, that various changes may be made in the details of construction, arrangement and combination of the various parts without departing from the spirit and scope of 40 our invention as defined in the appended claims.

In these drawings the numeral 2 designates a fuse block or carrier, which is shown 45 as of generally cylindrical form, and which is of some suitable insulating material, such as porcelain. It is provided at its respective ends with terminal members 3 and 4 of conducting material, and which are in the form of screw caps which can be readily screwed upon the threaded end portions 50 of the carrier.

5 designates the fuse members, which are 55 removably seated in spaced relation on the carrier. In the particular device shown,

there are eight complete fuse members, although we do not, of course, limit ourselves to this number, as a greater or less number may be employed. Each complete fuse member is formed in two parts, as is clearly shown in Figure 2, each part having a bent 60 end portion 6 engaging with a central recess 7 in the end of the carrier and also making contact with one of the terminals 3 or 4. The inner end of each fuse section is bent, as indicated at 8, and is engaged with 65 a recess 9 at the central portion of the carrier. The two sets of recesses 9 are separated from each other by the integral wall 10 of the porcelain body. The sections of the fuse members extend through the apertures 11 formed in said body. The external portion of the body is cut away centrally, as indicated at 12, adjacent to the inner ends of the sections of the fuse members. A sleeve 13 is rotatably mounted on the carrier over the opening formed by this cut-away portion, being held in place by an inturned lip 15 at one end, which engages with the shoulder 16 of the carrier, and also by a spring dog 17 secured to the sleeve and 70 adapted to snap into any one of a member of spaced depressions 18 formed in the outer peripheral surface of the carrier. Each of these depressions is preferably numbered, as indicated in Figure 1, so that it can be 75 determined at a glance just which fuse is in use, and how many have been used up.

The sleeve is shown as consisting of an inner metal lining with an outer covering 80 of some suitable insulating material, such as fiber. The inner metallic lining of the sleeve has a cut and inwardly bent portion 19 which acts as a brush or contact to span the adjacent inner end portions of the two fuse sections of one complete fuse member 95 and thus complete the fuse.

The operation will be readily understood. When any fuse member becomes destroyed, the sleeve is rotated one step, thus bringing the next pair of fuse sections into operation, and so on until all of the fuse members have been used. The terminal caps 3 and 4 can then be unscrewed and removed, together with the sleeve 13, and a new set of fuse sections can be inserted.

100 The advantages of our invention will be apparent to those familiar with devices of this kind. It provides a magazine or re-

repeater fuse in which the fuse members are at all times in electrical contact at both ends with the terminal members, but by reason of the divided character of each complete 5 fuse member only that fuse is actively in circuit which is engaged by the contact device of the rotatable sleeve. This sleeve forms a very simple and convenient means of making contact between the separated 10 sections of the fuse members and of shifting from one fuse member to another. The device is thus free of complicated contact parts of a character likely to become deranged and inoperative in use.

15 We claim:

1. A repeater or magazine fuse comprising a carrier having a plurality of fuse members, each of said fuse members being formed of two separated sections, and a movable 20 contact device for spanning the gap between the sections of any fuse member, substantially as described.

2. A repeater or magazine fuse comprising a carrier of insulating material having 25 removable terminal members at its ends, and a plurality of fuse members removably seated in spaced relation on said carrier, each of said fuse members being formed in two sections, each section being in contact with 30 one of the terminals and the two sections having separated end portions, together with a contact device adapted to span the separated end portions of each fuse member and to be moved from one fuse member to 35 another, substantially as described.

3. A repeater or magazine fuse comprising a carrier of insulating material, a terminal member removably engaged with each 40 end portion of the carrier, said carrier having a plurality of spaced seats for fuse elements, a plurality of fuse elements removably engaged with said seats, each of said elements being formed in two sections, each 45 of said sections being in contact with one of the terminals at one end and having their opposite ends separated from each other, and a sleeve member rotatably mounted on the carrier and having a contact device adapted to span the gap between the ends of the sections of any one of the fuse elements, substantially as described.

4. A repeater or magazine fuse comprising a carrier of insulating material, a terminal member of conducting material removably 55 engaged with each end of the carrier, said carrier having a plurality of seats for fuse elements and being cut away exteriorly at an intermediate portion, a plurality of fuse elements removably engaged with the seats 60 of said carrier, each of said fuse elements being formed of two sections and each section having one of its end portions in electrical contact with one of the terminal members, the opposite ends of said members being separated from each other, and a sleeve 65

rotatably mounted on the carrier and over the cut-away portion thereof and having a contact device for spanning the separated ends of the fuse sections, substantially as described.

5. A repeater or magazine fuse comprising a carrier of insulating material, a terminal member of conducting material removably engaged with each end of the carrier, said carrier having a plurality of seats for fuse 70 elements and being cut away exteriorly at an intermediate portion, a plurality of fuse elements removably engaged with the seats of said carrier, each of said fuse elements being formed of two sections and each section having one of its end portions in electrical contact with one of the terminal members, the opposite ends of said members being separated from each other, and a sleeve 75 rotatably mounted on the carrier and over the cut-away portion thereof and having a contact device for spanning the separated ends of the fuse sections, said sleeve being removable over one end portion of the carrier, substantially as described.

6. A repeater or magazine fuse comprising a carrier of insulating material, a terminal member of conducting material removably engaged with each end of the carrier, said carrier having a plurality of seats for fuse 80 elements and being cut away exteriorly at an intermediate portion, a plurality of fuse elements removably engaged with the seats of said carrier, each of said fuse elements being formed of two sections and each section having one of its end portions in electrical contact with one of the terminal members, the opposite ends of said members being separated from each other, and a sleeve 85 rotatably mounted on the carrier and over the cut-away portion thereof and having a contact device for spanning the separated ends of the fuse sections, said sleeve being removable over one end portion of the carrier, substantially as described.

7. A repeater or magazine fuse comprising a carrier of insulating material, a terminal member of conducting material removably engaged with each end of the carrier, said carrier having a plurality of seats for fuse elements and being cut away exteriorly at an intermediate portion, a plurality of fuse elements removably engaged with the seats of said carrier, each of said fuse elements being formed of two sections and each section having one of its end portions in electrical contact with one of the terminal members, the opposite ends of said members being separated from each other, and a sleeve rotatably mounted on the carrier and over the cut-away portion thereof and having a contact device for spanning the separated ends of the fuse sections, said sleeve and carrier having successively located cooperating

retaining means adapted to be successively engaged as new fuses are brought into use, substantially as described.

8. A repeater or magazine fuse comprising a carrier having a plurality of fuse members, each of said fuse members being formed in separated sections, and contact means forming a span for the spaces between the sections of the fuses whereby the sections of any fuse may be electrically connected, substantially as described.

9. A repeater or magazine fuse comprising a carrier of insulating material having removable terminal members at its ends, and

a plurality of fuse members removably seated in spaced relation on said carrier, each of said fuse members being formed in a plurality of separated sections adapted to be connected in series between the terminal members, and a contact device adapted to span the separated end portions of any desired fuse member for effecting said series connection, substantially as described.

In testimony whereof, we have hereunto set our hands.

HENRY P. DILLIG.
JOSEPH B. HILL.
